W. R. PETERS.
COMBINATION TOOL.
APPLICATION FILED JULY 8, 1919.

1,331,368.

Patented Feb. 17, 1920.

UNITED STATES PATENT OFFICE.

WALTER R. PETERS, OF PHILADELPHIA, PENNSYLVANIA, ASSIGNOR OF ONE-HALF TO
FRANCIS B. BEDDALL, OF PHILADELPHIA, PENNSYLVANIA.

COMBINATION-TOOL.

1,331,368.

Specification of Letters Patent. Patented Feb. 17, 1920.

Application filed July 8, 1919. Serial No. 309,282.

To all whom it may concern:

Be it known that I, WALTER R. PETERS, a citizen of the United States, residing in Philadelphia, Pennsylvania, have invented 5 Combination-Tools, of which the following is a specification.

My invention relates to combination tools, and the object of the invention is to provide a device combining certain tools pertaining 10 to the carpenters' trade with a saw of substantially standard form.

In the attached drawings:

Figure 1 is a view illustrating a tool embodying my invention; 15 Fig. 2 is a detail view in perspective of the miter attachment;

Fig. 3 is a vertical section of the miter attachment taken on line *a*—*a*, Fig. 2.

Figs. 4 and 5 are views in perspective, 20 showing details of the spring and set-screw; and

Fig. 6 is a partial view of a modified form of the tool.

With reference to the drawings, 1 indicates a combination tool constructed in accordance with my invention. In forming a tool I employ a saw, the greater portion of the upper edge 2 of which is straight, and such edge being properly graduated may 25 be utilized either as a straight edge or a scale. The saw may be of any desired length, but it is desirable that the length be such that the straight edge may be marked with a scale containing an even number of 30 inches. Near the butt of the saw a rounded projection 3 extends upwardly from the upper edge of the saw, said projection being apertured at 4 for the reception of a pivot bolt 5, which carries a miter attachment 6 35 illustrated in Fig. 2. The miter attachment 6 has a centrally disposed slot 7 extending from one end to a point short of the opposite end, in which latter end is the said pivot bolt 5. As indicated in Figs. 1 and 6, the 40 miter attachment is placed astraddle the upper edge of the saw blade and is held thereon by means of the pivot bolt 5, which extends through the aperture 4 in the projection 3. At the lower end of the miter attachment is a set-bolt 8, said set-bolt extending 45 across the slot 7 and entering into threaded engagement with the opposite leg of the miter attachment. Apertures 9, 9 are formed in the saw blade to accommodate the 50 passage of this set-bolt 8, the apertures being

disposed so that the miter attachment may be held at certain specified angles.

As indicated in Fig. 1, the apertures 9, 9 permit of the miter being held in position, giving angles ranging from zero to 90°. 60 Apertures may also be provided as shown in Fig. 6 for the accommodation of a pitch scale which may be marked upon the blade of the saw on the side opposite to that upon which the degree scale is established. The 65 pitch scale is illustrated in Fig. 6, which shows apertures 9^a, 9^a so disposed as to give inclinations of the miter attachment giving pitches from $\frac{1}{4}$ inch to 1 inch. In order to give the miter attachment the extent of 70 swing required for scales of the described capacity, the top edge of the saw blade is depressed at 10 for the reception of the upper end of the miter block, and this depression permits a movement of the miter attachment to the position indicated by dotted 75 lines in Fig. 1.

When the saw itself is to be used, the miter attachment may be swung back so that it lies within a recess 11 provided in the 80 body of the handle 12. A level 13 may be provided upon the miter attachment as shown in Fig. 2, the level being so placed as to be capable of being read from the top or side as desired. The level 13 may consist of 85 a bubble tube 14 held in a considerable depression upon the miter block by means of a metal guard 15 screwed or held in any suitable manner to the miter block. In order that the set bolt 8 may be held away 90 from the apertures 9, 9^a when the miter block is being swung to a new angle, a spring 16 is provided, said spring having one end attached to the miter block by means of a screw 17, while the other end is attached in 95 suitable manner to the set-bolt 8. This spring 16 tends to hold the set-bolt in the position indicated in Fig. 2, in which position the lower end of the bolt is held well away from the slot 7 in the miter block. A vertical level 19 is placed upon the body of the handle 12 and is held thereon in substantially the same manner that the level 13 is held upon the miter block. This level 19 is mounted in a position paralleling the 100 straight edge 2, and it will be evident that this level may be used in conjunction either with the said straight edge 2, or with the miter block when the latter is placed so as to form an angle of 90° with the said straight 105 110

edge, and there is, therefore, no essential need for a level placed in the miter block itself.

The manipulation of the device will be apparent. When it is desired to use a saw for cutting, the miter block may be swung back within the recess provided for it in the body of the handle in which it can in no way interfere with the operation of the saw. The manipulation of the miter block is similar in every way to the manipulation of any tool of the sort, the necessary straight edge being provided by the upper edge 2 of the saw blade, while the vertical and horizontal levels are provided by the levels 19 and 13 upon the saw handle and upon the miter block respectively; and also provision is made for the obtaining of the miter reading in terms of degrees of the angle or pitch that is desired.

In the modification shown in Fig. 6, the projection 3 is eliminated and a straight back saw of standard form is employed. In this form it is necessary to enlarge the depression 10, which receives the upper end of the miter, this enlarged depression being indicated in Fig. 6 by the numeral 10^a, it being necessary to modify the form of the handle as well, to provide for the necessary amount of travel of the miter block.

I claim:

1. A saw comprising a handle; a blade having a straight upper edge attached to said handle; a miter block carrying a pivot; an aperture in said blade for the reception of said pivot; a set-screw in the lower end of said miter block; a scale marked on said saw blade, said scale being marked along a segment of a circle of which the aperture carrying said pivot is the center; apertures in the said saw blade to receive said set-screw in holding the miter block at the desired point on said scale; and a spring attached to said miter block and to said set-

screw for holding said set-screw away from engagement with said apertures while the miter block is being moved to a new position.

2. A saw comprising a blade having a substantially straight upper edge, a handle attached to said blade, an apertured lug extending above the upper edge of said blade, a miter block carrying a pivot bolt, said bolt being mounted within said apertured lug, a recess within said handle for the reception of the miter block, and means for retaining the miter block at the desired angle with respect to the upper edge of the blade.

3. A saw comprising a handle, a blade having a straight upper edge attached to said handle, an apertured lug extending above said upper straight edge, a miter block carrying a pivot, said pivot being mounted on said apertured lug, a set-screw in the lower end of said miter block, a scale marked on said saw blade, said scale being marked along a segment of the circumference of a circle of which the aperture in said lug is the center, and apertures in said saw blade to receive said set-screw in holding the miter block at the desired point on said scale.

4. A saw comprising a blade having a substantially straight upper edge, a handle attached to said blade, a miter block pivoted to said blade at said upper edge, said miter block having a portion thereof extending above said upper edge and having portions thereof extending down each side of said blade, and a depression in the upper edge of said blade for accommodating the said upwardly extending portion of the miter when said miter is swung to the position in which it forms the least angle with the said straight edge.

In witness whereof I affix my signature.

WALTER R. PETERS.
